Heinrich Koflers

Inventor.

Dr: - Monday, Clarke & Carpenter Atty's

UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

OVEN FOR BURNING REFRACTORIES AND THE LIKE.

Application filed August 31, 1921. Serial No. 497,369.

(GRANTED UNDER THE PROVISIONS OF THE ACT OF MARCH 3, 1921, 41 STAT. L., 1313.)

To all whom it may concern:

Be it known that I, HEINRICH KOPPERS (assignor to The Koppers Development Corporation, a corporation of Pennsylvania), 5 a citizen of Germany, residing in Essen-Ruhr, Germany, have invented a new and useful Improvement in Ovens for Burning Refractories and the like, of which the following is a specification.

10 The invention relates to ring furnaces for burning ceramic ware, lime, dolomite, and the like.

According to another invention of mine there is solved the problem of operating in 15 a quite definite manner the individual chambers of a ring furnace serving consecutively as preheating, burning, and cooling chambers, which possess not only direct access openings at the floor but also conveying 20 ducts leading from the furnace roof to the floor of the chambers. In the chambers acting as preheaters both these paths are always open, and when the last preheating chamber is about to operate for burning in 25 instead of preheating the lower opening is closed by a sand filling; on the emptying of the chambers containing the fully burnt and cooled ware these sand seals are again opened from the side of the chamber by 30 scooping or scraping them out. In this way it is possible to use actual sand seals, that is, seals whose formation and removal are effected without employing flaps, slides and the like; in other words, there are obtained 35 closures resembling liquid seals, having no mechanism.

According to the present development this idea, so useful for the formation of these lower seals, is also adopted for the conveying 40 ducts leading from the furnace cover to the side of the chamber, whereby valves, flaps, slides and the like are dispensed with throughout the furnace structure and the operation carried on with sand seals or closures exclusively, which are produced and destroyed corresponding to their nature and location. This is attained by the plan that 45 through the openings or passages formerly required in the furnace roof at the upper ends of the conveying ducts, sand is now filled in, which falls into the bend of the channel around the intermediate partition

and thereby forms a seal; by suitable formation of this cavity below the intermediate partition, viz, by a suitable bevelling 55 towards the interior of the chamber, removal at any time of the sand seal can be effected here also by scraping or scooping. By this arrangement not only is the furnace construction unified but also a simplification 60 in operation is attained, since the handling of all the seals takes place according to the same rules.

In the accompanying drawing a constructional example of the subject matter of the 65 invention is shown, for the purposes of illustration and explanation of the invention but not to limit the same to details, in which drawings—

Fig. 1 is a vertical section of a portion of 70 a ring furnace embodying the invention, on line I—I of Fig. 3.

Fig. 2 is a similar view on line II—II of Fig. 3.

Fig. 3 is a horizontal section on line 75 III—III of Fig. 1.

The individual chambers 10 to be arranged in ring operation are charged through the openings 25 with fresh material, and serve in turn as preheating, burning, 80 and cooling chambers. The arrangement at any time is effected exactly as in my United States application Serial No. 497,367 filed Aug. 31, 1921. The direct passage of the gases from one chamber into the other takes 85 place through cavities 18 made under the partitions 11, which when necessary can be filled from the top with sand through the passages 19. The sand can be scraped or scooped out as required, from both sides, 90 to allow which operation the floor of the cavity 18 is suitably bevelled off. The conveying ducts 13 leading from the furnace roof to the floor are also provided with cavity like bends 27 under the partition 11, 95 which however differ from the cavities 18 by being open on one side only. Through pipes 26 arranged in the partitions 11 sand can also be filled when necessary into the cavities 27 to form a seal here, which can 100 be again broken after opening the corresponding chamber 10. The burning is effected by gas supplied through the channels 15, which enters by nozzles 28 in the vicinity

of the cavities 27, to which is supplied the highly heated combustion air from the cooling ware. As can be seen from the plan, the channels 13 are always arranged alternately with the cavities 27 and the cavities 18 so that a uniform distribution over the whole width of the burning chamber is obtained.

What is claimed is—

1. A ring furnace for burning ceramic ware and the like comprising a plurality of chambers, partitions separating said chambers, ports at the lower ends of said partitions communicably connecting the lower portions of adjacent chambers with each other, ducts communicating with each of said ports through which means may pass to shut off communication through said ports, other ports at the lower ends of said partitions, said ports communicably connecting with an upwardly extending channel, said last mentioned ports and channels communicably connecting the lower portion of one chamber with the upper portion of the next adjacent chamber, ducts leading to each of said last mentioned channels and ports through which means may pass to shut off communication through said ports.
2. A ring furnace for burning ceramic ware and the like comprising a plurality of chambers each adapted to preheat, burn and cool material, partitions separating said chambers, ports at the lower ends of said partitions communicably connecting the lower portions of adjacent chambers with each other, ducts leading to each of said ports to facilitate closing of said ports, other ports at the lower portions of said partitions, said ports communicably connecting the lower portions of one chamber with an upwardly extending channel, the upper end of said channel communicating with the upper portion of an adjacent chamber and sand ducts leading to said channel and with an upwardly extending channel, the upper end of said channel communicating with the upper portion of an adjacent chamber and sand ducts leading to said channel and

said last mentioned ports to facilitate closing of said ports.

3. A ring furnace for burning ceramic ware and the like comprising a plurality of chambers, partitions separating said chambers, ports at the lower ends of said partitions communicably connecting the lower portions of adjacent chambers with each other, ducts communicating with each of said ports through which sand may pass to shut off communication through said ports, other ports at the lower ends of said partitions, said ports communicably connecting with an upwardly extending channel, said last mentioned ports and channels communicably connecting the lower portion of one chamber with the upper portion of the next adjacent chamber, ducts leading to each of said last mentioned channels and ports through which sand may pass to shut off communication through said ports.

4. A ring furnace for burning ceramic ware and the like comprising a plurality of chambers each adapted to preheat, burn and cool material, partitions separating said chambers, ports at the lower ends of said partitions communicably connecting the lower portions of adjacent chambers with each other, sand ducts leading to each of said ports to facilitate closing of said ports, other ports at the lower portions of said partitions, said ports communicably connecting the lower portions of one chamber with an upwardly extending channel, the upper end of said channel communicating with the upper portion of an adjacent chamber and sand ducts leading to said channel and said last mentioned ports to facilitate closing of said ports.

In testimony whereof, I have hereunto set my hand this 26th day of July, 1921.

HEINRICH KOPPERS.
